UNITED STATES PATENT OFFICE.

BENJAMIN FELAND GROAT, OF PITTSBURGH, PENNSYLVANIA.

METHOD OF AND MEANS FOR CONTROLLING THE SURFACE TRANSPORTIVITY OF STREAMS, &c.

1,314,743.

Specification of Letters Patent.

Patented Sept. 2, 1919.

Application filed December 12, 1917. Serial No. 206,793.

To all whom it may concern:

Be it known that I, BENJAMIN FELAND GROAT, a citizen of the United States, residing at Pittsburgh, in the county of Allegheny and State of Pennsylvania, have invented certain new and useful Improvements in Methods of and Means for Controlling the Surface Transportivity of Streams, &c.; and I hereby declare that the following is -10 a full, clear, and exact description thereof, reference being had to the accompanying drawings, which form part of this specification.

This invention includes both a novel 15 method of and novel means for controlling the surface flow of water or fluid in rivers, streams, sounds and canals so as to prevent the same becoming clogged, jammed or disadvantageously affected by floatage, such as 20 ice, wood, or other materials which float upon or are suspended in or near the surface of the water or fluid.

The principal objects of the invention are first, to insure the desired surface velocity 25 of the water at any point or points, so as to carry away and prevent clogging or jamming of the floatage. Second, to prevent the floatage being carried into any lateral duct, such as a canal or race leading from the 30 stream or river by so controlling the surface current of the water at the mouth or intake of the canal that the floatage will be directed away from the canal and past the mouth thereof and not be permitted to enter into 35 the same; and third, to provide a novel method and means whereby sub-surface water may be diverted into the canal beneath the surface or part of the main stream carrying the floatage, so that no floatage will be carried into such steam.

For sake of brevity in the following explanation, I will refer to all materials such as ice, wood and the like usually carried on or near the surface of the water as "floatage". I will refer to the main body of the water, the flow of which is to be directed, as a stream, and to the lateral flow of such water or conduit as a canal; and the word 45 fluid may be substituted for the word water, as my invention may be applied to any channels conveying a fluid containing floatage under circumstances anywise analogous to those hereinafter referred to. The terms

"floatage", "stream", "water" are to be understood as being general and not definitive 55 terms.

I will explain certain specific utilizations of the invention hereafter to enable others skilled in the art to adapt and use the same, and to facilitate an understanding thereof 60 will refer to the accompanying drawings, which conventionally illustrate some applications thereof, and the essential features of the invention for which protection is desired are summarized in the claims. 65

In said drawings:

Figure 1 conventionally illustrates how the invention may be applied to a stream to prevent accumulation or jamming of floatage at a portion thereof where such jamming is 70 apt to occur.

Fig. 2 is a sectional elevation on the line 2-2, Fig. 1.

Fig. 3 conventionally illustrates a stream with a canal drawing water therefrom and 75 an arrangement according to my invention whereby floatage is prevented from entering a canal.

Fig. 4 is a sectional elevation on the line 4-4, Fig. 3.

Fig. 5 conventionally illustrates another arrangement according to my invention for preventing floatage entering a canal.

Fig. 5^a is a detail section on line 12-12 Fig. 5.

Fig. 6 is a sectional elevation on the line 6-6, Fig. 5.

Figs. 7, 8, 9, 10 and 11 are detail views illustrating the various methods of forming the ridges or channels in the stream for 90 maintaining or accelerating the surface flow thereof at points desired.

The method consists essentially in directing and accelerating the motion of the water at and near the surface thereof so 95 that the floatage will be carried away from the places in which jams, or congestions thereof are likely to occur, thus producing transporting surface currents capable of carrying the floatage away from places where 100 it is not wanted.

Jams of floatage, such as ice, wood, lumber, grass, dead bodies, or other débris frequently occur in reaches, or pools of streams where the floatage enters the pool in greater quantity than can be transported away by 105

the outflowing surface currents, and my invention can be advantageously used in such case as follows:

Referring to Fig. 1, 1 designates a large deep pool fed by a wide but shallow stream from above and discharging through a narrow and deep outlet 2 of relatively large sectional area. Under these circumstances, during winter, ice may be fed into the pool 10 at a very rapid rate while the outlet 2 being insufficient to discharge it, an ice jam results.

The capacity of the stream to discharge matter at or near its surface depends primarily, though not entirely, upon the intensity and extent of the surface currents at the particular place involved. The product of the width and mean surface velocity of the stream at the place will be a more or 20 less exact measure of said capacity, which, for brevity, I will herein call "surface transportivity" of the stream.

One very simple application of my method consists in reducing the effective depth of 25 such narrow and deep outlet 2 in order to increase the surface transportivity or flow sufficiently to carry off the floatage and prevent the formation of a jam at such outlet.

When said transportivity is greater above 30 than below the pool a jam may occur at or near the outlet when there is a sufficiently rapid supply of floating materials. The desired increase of surface transportivity may be attained by raising the average elevation 35 of the bed of the stream in and adjacent the outlet 2, as by forming the sub-surface ridge, or submerged dam 8, or several such ridges, or dams 8, extending transversely across, or partially across, the channel of the stream, or at any suitable angle, or angles 40 relative to the general direction of flow.

Said ridges 8 may extend partially or wholly across said channel, as circumstances 45 may require, and they may or may not be parallel one with another and may or may not rise to the same elevation. The surface transportivity may also be augmented by widening the outlet at the same time reducing its effective depth, as aforesaid, by 50 ridges or dams below the surface of the water therein.

These sub-surface ridges or dams may be constructed of excavated material, or of sheet metal, sheeting, metal sheet piling, 55 sheet piling, concrete piling, and ordinary timber piling. In other cases earth, timber, stone, masonry or concrete may be employed. Some forms of such ridges or dams are indicated in Figs. 7 to 11, hereinafter 60 referred to.

A very important application of my invention is in connection with the diversion of water from the stream into a canal or race leading from the stream to a plant or 65 point of utilization of a water supply, where

the intake of the canal must be protected from floatage, and my invention enables the surface transportivity of the main stream, or canal, or both, to be so controlled as to impel all or at least the greater portion of 70 the surface water in the stream, past the intake of the canal, beyond, below and away from the intake, so as to prevent floatage entering the canal.

It is not meant that any particular part 75 of the water must remain at the surface and be impelled at the accelerated speed down the main channel, but it is intended that all or at least the greater portion of 80 the water surface in the stream must move down stream in the main channel without being diverted into the canal. Such utilizations of the invention are illustrated in Figs. 3 to 6.

As shown in Fig. 3 the intake of the canal 85 5 is located at a bend either natural or artificially formed for the purpose in the stream 6 so that the surface flow of the current is slightly away from the mouth of the canal. In such case I form in the bed 90 of the stream adjacent the mouth of the canal and extending toward the intake thereof, a series of dams or channels and ridges, which are so formed as to maintain or increase the surface transportivity or flow of 95 the water in the stream past the intake of the canal and sufficiently away from the intake to insure that the floatage will not enter the intake of the canal, but will pass the same.

The channels and ridges 8 may be formed in various ways: The channels may be dredged into or built upon the original bed, or upon a lower level after excavating the bed of the main stream in a transverse or 105 oblique direction at any suitable angle with reference to the direction of the main current, and leading toward or into the entrance to the divergent canal and if the channels are made by dredging the original 110 river bed the ridges 8 can be formed by the portions left between the channels as indicated in Fig. 7; and if desired the excavated soil from the channels may be piled upon the ridges 8 as indicated at 8^a 115 in Fig. 8, thus, increasing the height of ridges and also the depth of the channels. Where dredging is not convenient or desirable the ridges might be formed by suitable piles driven or sunk close together, as 120 indicated at 8^b in Fig. 9; and the spaces 7^b between the rows of piles form the channels. The body of water in the channels 7^b between the rows of piling 8^b has no bodily movement down stream, but can flow laterally into the canal. If the bottom of the stream should be of rock the channels 7^b could be cut therein and the ridges 8 could be heightened by building a masonry or concrete coping 8^c thereon as indicated in Fig. 130

10. If it is not desirable to excavate the bottom the ridges might be formed by cribs 8° of any suitable kind, see Fig. 11, which cribs may be filled with rock and the 5 spaces 7° between the cribs correspond to the channels.

In all cases the channels and ridges should be sufficiently below the surface of the water not to interfere with the floatage.

10 and sufficiently extensive to insure that the surface transportivity shall be increased or accelerated to such an extent as will insure the desired control of the surface currents and therefore of the floatage.

15. When several of the transverse channels and ridges are employed in making a sub-surface diversion it will be of advantage to have the crest of each successive ridge rise to a higher elevation than that of the crest 20 of the next ridge upstream, and the surface transportivity of the main current progressing down stream may be increased, notwithstanding that water is being diverted from it beneath the surface to a 25 canal through the transverse or oblique channels as the main current flows over them. In some cases it may be desirable to build different ridges to different elevations to control the flow of water and 30 floatage even though no sub-surface diversion is made.

Referring to Figs. 3 and 5, it is evident that water must flow from the main stream to the canal if water is being withdrawn 35 through the canal. This will cause a tendency, greater or less in amount, of all parts of the water in the main channel and the transverse, or diversion, channels to flow toward the canal, since the water taken from 40 the canal would naturally cause a fall of the water surface within the canal, at the canal intake, and this would cause a diversion of water from the main stream into and through the diversion channels toward and 45 into the intake of the canal.

But the ridge of ridges 8 cause the surface water in the main stream to flow rapidly down the main channel while the water in the submerged transverse, or oblique diversion channels between the ridges and below 50 their crests can flow with facility only in the direction of or toward the intake of the canal.

If the widths of the stream and intake of 65 canal, the elevations of the crests of the ridges, the depths of the transverse channels and the geographical configuration in the vicinity of the intake have received proper attention and are properly designed and 70 arranged, the surface current in the main stream will not be impelled toward the intake sufficiently to cause any of the water at the surface to move into the intake and down the canal while it is at the surface.

85 My invention also contemplates the uses

of jetties, dikes, wing dams or other structures which can be employed for the purpose of deflecting water or reducing the effective widths of channels when they are too wide. Such jetties or the like when 70 employed in combination with my sub-surface channels or ridges for controlling the flow of streams for the purposes specified form a part of my invention.

When the configuration of the shores and 75 ground in the vicinity of the intake is unfavorable and requires it, a jetty, or like structure, indicated at 10 in Fig. 5 may be built so as to project into the main stream from the shore adjacent the upstream side 80 of the intake, for the purpose of deflecting the water in the stream away from the intake and preventing a flow of the surface water from the upstream side into the intake, notwithstanding that it is intended to make 85 the sub-surface diversion to avoid said surface flow into the intake. Such jetties assist the subsurface diversion by decreasing the width of the main stream so as to increase 90 the velocity of the main current and by increasing the curvature of the main currents on account of the deflection produced so as to increase the pressure toward the divergent canal upon the portions of water at and near the bottom of the stream. The 95 wing or jetty 10 may be provided at top with a projecting flange or overhanging portion 10° on its instream side for holding ice away from the central portion of the structure and directing it away from the eddy 100 that usually forms in water at the downstream extremity of a jetty or wing; this overhang is more clearly shown in Fig. 5.

In some cases where the sub-surface channels are used so as to direct the water from 105 beneath the surface of the stream into the canal, as above described, the mouth of the canal may be narrowed by a wing dam as indicated at 11 in Fig. 5, so that sufficient water may be supplied to the canal through 110 the submerged channels and the transverse acceleration of the surface current in the stream will be increased and the floatage prevented entering the canal below the lowermost or farthest down-stream channel. 115 In some cases also the main stream may be narrowed by a wing as indicated at 12 in Fig. 5 or by another structure as indicated at 12A, Fig. 5, which, by narrowing the passage also tends to accelerate the surface flow 120 of the water past the intake of the canal and concentrates the flow over the diversion elements, thus reducing the amount and cost of construction.

By my invention the water is so controlled 125 at the intake of the canal and in the main stream in the vicinity of the intake that no surface water, and therefore no floatage will enter the canal from the main stream. With sufficient channels and dams the surface 130

transportivity in the intake of the canal can actually be made negative so that at the surface the water will flow outwardly from the intake into the main stream, the canal 5 receiving a sufficient supply of water from the sub-surface channels or under part of the main stream to take care of the combined requirements of the canal and the return currents at the intake. This effect can be 10 produced with more or less intensity by making what I call a sub-surface diversion of water to the canal from the lower portions of the main stream in greater amount than would be necessary simply to supply 15 the water required for the canal. The result of this is that the excess water diverted sub-superficially causes a counter, or compensating surface current flowing outwardly from the intake into the main stream.

20 I claim:—

1. The method of controlling the surface transportivity of streams, consisting in altering the depth of the stream by a sub-surface structure adjacent the point where 25 change in its surface transportivity is desired.

2. The method of controlling the surface transportivity of a stream, consisting in locating an angularly disposed structure 30 below the surface of the water adjacent the point where it is desired to change the surface transportivity.

3. The method of controlling the surface transportivity of streams, consisting in forming below the surface of the streams adjacent the desired point a plurality of adjacent ridges disposed at any angles to the line of flow of the stream.

4. The herein described method of preventing floatage collecting in streams, consisting in shallowing the stream at the desired point by artificial means sufficiently to increase the velocity of the surface water of the stream to insure carrying the floatage 45 past such point.

5. The herein described method of preventing floatage collecting in streams, consisting in placing submerged structures in the streams at the points where it is desired 50 to increase the velocity of the surface water of the stream sufficiently to insure carrying the floatage past such point.

6. The herein described method of preventing accumulation of floatage in streams, 55 consisting in forming in the streams a series of submerged ridges or dams and successively increasing in height down stream.

7. In the art of diverting water from a main stream into the intake of a divergent 60 water way to secure water free from floatage, the method which consists in causing a layer of water next the surface of the main stream to flow in a curved path concave in a horizontal direction toward the place where the 65 diversion is to be made, simultaneously al-

lowing the potential thereby produced to force water out of the lower portions of the main stream into the intake of the divergent water way, substantially as and for the purposes herein described.

8. The method of diverting water from a stream into a canal, consisting in providing a channel at an angle to the line of flow of the stream and below the surface of the stream, whereby water is directed from the 75 lower portion of the stream into the intake of the canal.

9. The method of making a sub-surface diversion of water from a stream into a canal leading therefrom whereby water is directed 80 into the canal below the water level while the surface water in the stream and intake of the canal is diverted away from the intake of the canal and on down the main stream; consisting in forming a transverse or oblique channel in the bed of the river extending 85 toward the intake of the canal.

10. The herein described method of preventing floatage entering the intake of a canal connected with a stream; consisting in 90 providing a plurality of submerged ridges in the stream adjacent the intake to increase the velocity of the surface water of the stream and carry the floatage past such intake.

11. The method of making a sub-surface diversion of water from a stream into a canal leading therefrom, whereby water is directed 100 into the canal below the water level while the surface water in the stream and inlet to the canal is diverted away from the inlet and on down the main stream; consisting in forming a plurality of transverse alternating channels and ridges in the bed of the river extending toward the intake of the 105 canal; and providing wing dams adjacent the intake.

12. The herein described method of preventing floatage entering the intake of a canal connected with a stream; consisting in 110 providing a plurality of submerged alternate ridges and channels in the stream adjacent the intake to increase the velocity of the surface water of the stream sufficiently to carry the floatage past such intake, and 115 to divert sufficient water from the stream, below its surface, into the canal to supply the latter.

13. Means for controlling subaqueously 120 the surface transportivity of a stream, consisting of an appropriate number of subaqueous ridges forming suitable elevations of parts of the bed of the stream, each lying in a direction at an angle with the current.

14. Subaqueous means for controlling 125 simultaneously the transportivities of a main stream and diverting channel in the vicinity of the intake of the diverting stream, consisting of a suitable number of channels bordered by marginal banks of 130

suitable elevations formed in the bed of the main stream and constituting a subaqueous waterway below the flow of the current in the main stream and leading toward the diverting stream, whereby water is made to flow subsuperficially into the diverting channel while surface water in the main stream, with any floatage therein, is diverted away from the entrance to the diverting stream and on down the main stream.

15. Means for making my subsurface diversion of water from a main stream into a channel leading therefrom, whereby water is made to flow into the divergent channel considerably below the water surface, while the surface water in the vicinity of the entrance to the diverting channel, with any floatage therein, is diverted on down the main stream; consisting of a subaqueous 20 waterway formed by an appropriate number of subaqueous ridges of suitable elevations upon the bed of the main stream and leading toward the diverting channel.

16. Means for diverting water from a stream to a canal leading therefrom, comprising a plurality of channels of suitable depths disposed at an angle to the line of flow of the stream adjacent the intake of the canal and below the surface of the 30 stream, whereby water is taken from the lower portions of the stream into the intake of the canal.

17. Means for diverting water from a stream to a canal leading therefrom, com-

prising a plurality of alternate ridges and 35 channels disposed at angles to the lines of flow of the stream adjacent the intake of the canal and below the surface of the stream, whereby water is taken from the lower portions of the stream into the intake 40 of the canal, and entry of floatage into the intake of the canal is prevented.

18. Means for making a sub-surface diversion of water from a stream into a canal leading therefrom, whereby water is directed into the canal below the water level while the surface water in the stream and intake to the canal is diverted away from the intake to the canal and on down the main stream; comprising a plurality of alternating 45 submerged channels and ridges arranged transversely to the stream and extending toward the intake of the canal; and suitable wing dams adjacent the intake.

19. Means for preventing the entrance of 55 floatage into canals connected with streams, consisting in forming in the stream a series of submerged alternating ridges and channels disposed at angles to the flow of the main stream to increase the surface flow of 60 the water at such point past the mouth of the canal and to direct water beneath the surface of the stream into the intake of the canal.

In testimony that I claim the foregoing 65 as my own, I affix my signature.

BENJAMIN FELAND GROAT.

It is hereby certified that in Letters Patent No. 1,314,743, granted September 2, 1919, upon the application of Benjamin Feland Groat, of Pittsburgh, Pennsylvania, for an improvement in "Methods of and Means for Controlling the Surface Transportivity of Streams, &c.," an error appears in the printed specification requiring correction as follows: Page 2, line 114, for the word "soil" read *soil*; and that the said Letters Patent should be read with this correction therein that the same may conform to the record of the case in the Patent Office.

Signed and sealed this 7th day of October, A. D., 1919.

[SEAL.]

M. H. COULSTON,

Acting Commissioner of Patents.

Cl. 61—2.
